UNITED STATES PATENT OFFICE.

GEORGE WASHINGTON THOMAS, OF YOSEMITE, KENTUCKY.

COMBINED POST AND WIRE-STRETCHER.

No. 810,232.

Specification of Letters Patent.

Patented Jan. 16, 1906.

Application filed September 6, 1905. Serial No. 277,227.

To all whom it may concern:

Be it known that I, GEORGE WASHINGTON THOMAS, a citizen of the United States, residing at Yosemite, in the county of Casey and State of Kentucky, have invented a new and useful Combined Post and Wire-Stretcher, of which the following is a specification.

This invention relates to combined posts and wire-stretchers, and has for an object to provide a device of the class embodying new and improved features of simplicity, durability, utility, and efficiency.

A further object of the invention is to provide a post having staples, hooks, or lugs to engage the wires and a notched stretching-strip to loop the wire between the lugs, hooks, or staples so as to take up and hold the slack.

A further object of the invention is to provide means whereby the wire after being looped may be secured to the post and the stretching-strip removed, if desired.

A further object of the invention is to provide means whereby the stretching-strip may be removed and the post employed in association with boards to construct a board fence.

A further object of the invention is to provide a post which may be used for constructing a picket fence or in association with any form of fabric or ornamental fencing.

A further object of the invention is to provide a post which may be secured and used in combination with any approved form of base, such as concrete, terra-cotta, metal, or the like.

With these and other objects in view the present invention consists in the combination and arrangement of parts, as will be herein-after fully described, shown in the accompanying drawings, and particularly pointed out in the appended claims, it being understood that changes in the form, proportion, size, and minor details may be made without departing from the spirit or sacrificing any of the advantages of this invention.

In the drawings, Figure 1 is a perspective view of a fence embodying the invention. Fig. 2 is a perspective view of the reverse or rear side of the post. Fig. 3 is a transverse sectional view of the post. Fig. 4 is a top plan view of the post. Fig. 5 is a view of the stretching-strip in side elevation. Fig. 6 is a perspective view of the post member of the invention associated in a board fence. Fig.

7 is a perspective view of a modified form of post.

Like characters of reference indicate corresponding parts in all of the figures of the drawings.

In its preferred embodiment the invention forming the subject-matter of this application comprises a post member composed of the front plate 10, the back brace 11, provided with the openings 12, and of any approved length to be embedded or secured in any approved manner in or upon a base of any desired shape and material and shown conventionally at 13 and the post shown in Fig. 2 as broken to indicate that the lower end may be of any added length and form.

Upon the edges of the front plate 10 are the staples or hooked lugs 14, arranged in pairs aligned transversely of the post, and somewhat above each pair of lugs and adjacent the vertical middle of the plate 10 are formed holes 15. At the upper end of the post a flange 16 is disposed outstanding in front of the plate 10, said flange being provided with an opening 17. Through the opening 17 is inserted the upper screw-threaded end of the stretching-strip 18, having notches 19 formed along one edge 80 in position to engage the wires 20 and having a nut 21 upon the screw-threaded portion and bearing upon the flange 16. After the wires 20 between the hooks, staples, or lugs 14 are engaged within the notches 19 the nut 21 is tightened, drawing the strip and wires to the positions shown on the left-hand post in Fig. 1, when the stretcher-strip will hold the wire taut and be in position to compensate for any expansion or contraction of the wires.

Attention is called to the fact that the side of the post between the wire-engaging lugs is flat and unobstructed, thereby forming a bearing-surface for the fence-wires and also for the vertically-movable stretching-strip, while the notches 19, being formed in the inner face of the stretching-strip, said wires are prevented from becoming accidentally displaced during the stretching operation.

In the form shown in Fig. 7 the staples 25 are substituted for the hooked lugs 14 in case the post is made of wood or other penetrable material.

In practice it may be found unnecessary to have the strips 18 on every post, in which

case pins or staples 22 may be inserted in the holes 15 beneath and to support the wires.

The post may be used with boards by securing the boards 23 to the post by the wires 24 through the holes 15 and with the upper end of the top wire through the opening 17 in the flange 16.

For use in association with fabric or ornamental fencing the holes 12 in the brace-rib 11 may be used, as by passing wires through the said holes or tying therein. The post may be made of metal, wood, or any desired material.

From the foregoing description it is believed the use, operation, and advantages of the improved post and wire-stretcher will be fully understood and appreciated.

Having thus described the invention, what is claimed is—

1. A fence-post comprising a standard having one side thereof formed with a flat bearing-surface provided with spaced downwardly-extending wire-engaging lugs, a vertically-adjustable stretching-strip movable over the flat bearing-surface of the post and having its inner face provided with spaced notches adapted to engage the wires between

the lugs for stretching said wires longitudinally of the post, and means for locking the stretching-strip in adjusted position.

2. A fence-post comprising a standard having one side thereof formed with a flat bearing-surface and one end with a laterally-projecting flange provided with a threaded opening, there being spaced downwardly-extending wire-engaging lugs formed on the opposite longitudinal edges of the flat side of the post, a vertically-adjustable stretching-strip movable over the flat bearing-surface of the post and having one end thereof threaded for engagement with the opening in the flange and its inner face provided with a series of spaced notches adapted to engage the wires between the lugs, and a nut threaded on the strip and engaging the flange for locking the stretching-strip in adjusted position.

In testimony that I claim the foregoing as my own I have hereto affixed my signature in the presence of two witnesses.

GEORGE WASHINGTON THOMAS.
